Primary Examiner — Jennifer Rivard*(74) Attorney, Agent, or Firm* — John M. Lipchitz(57) **CLAIM**

The ornamental design for a shaving razor handle, as shown and described.

DESCRIPTION

FIG. 1 is a front perspective view of a shaving razor handle showing our new design;

FIG. 2 is a top view thereof;

FIG. 3 is a bottom view thereof;

FIG. 4 is a right view thereof;

FIG. 5 is a left view thereof;

FIG. 6 is a rear view thereof;

FIG. 7 is a front view thereof; and,

FIG. 8 is a rear perspective view thereof.

The broken lines showing the razor cartridge illustrate the environment and the remaining broken lines illustrate portions of the handle. None of the broken lines form part of the claimed design.
